UNITED STATES PATENT OFFICE.

SAMUEL SMITH, OF PROVIDENCE, RHODE ISLAND.

SWIVEL WATER-DISPLACER FOR DRYING-CYLINDERS.

SPECIFICATION forming part of Letters Patent No. 739,354, dated September 22, 1903.

Application filed March 2, 1903. Serial No. 145,631. (No model.)

To all whom it may concern:

Be it known that I, SAMUEL SMITH, of Providence, in the State of Rhode Island, have invented a new and useful Swivel Water-Displacer for Drying-Cylinders; and I do hereby declare that the following specification, taken in connection with the drawings making a part of the same, is a full, clear, and exact description thereof.

10 Figure 1 is a plan or face view of my device. Fig. 2 is a longitudinal or vertical section of same. Fig. 3 is a view of the reverse of Fig. 1. Fig. 4 is an end view of a drying-cylinder, showing my device in dotted lines. Fig. 5 is 15 a horizontal section of same.

My invention is designed to remove the water resulting from condensing steam from the interior of drying-cylinders whether the same are in operation or at rest; and it consists in 20 the device attached, arranged, and operating within such cylinders hereinafter described. The principal device now in use for this purpose is in the nature of a scoop, which consists of two hollow arms attached to and connected with a hollow arbor, which forms the 25 axis and through which the cylinder is rotated. The arms extend outward from the axis in the same plane, terminating in a socket or scoop which is divided or partitioned 30 longitudinally, such partition extending outward beyond the face of the socket and coming in close proximity to the interior wall of the cylinder. As the cylinder rotates the water seeking its level comes in contact with 35 the extended partition and is diverted into the concave scoop or socket and passes through the hollow arm to which the socket is attached and into and through the hollow axis of the cylinder and passes off, as will be readily understood. The difficulty experienced in the 40 use of these devices is, first, their frequent and serious disarrangement, and, second, their inability to perform any work when the cylinder is at rest. Their operation is entirely dependent upon the rotary movement 45 of the cylinder.

The purpose of my invention is to provide a device which will be capable of a positive action at all times without in any way being 50 dependent upon the movement of the cylinder and one which will not get out of order

and suspend the operation of the machine for the purpose of repairs.

In the drawings, A is a cylindrical receptacle, cup, or box for receiving the water, 55 having a flange B, by which it is attached to the cast-iron head C upon the inside of the cylinder. The interior opening of the box A after its attachment to the head C will be in a horizontal plane with the central opening 60 through the axis D of the cylinder. The box A is also provided with a series of circumferential perforations or openings E, through which the water may enter.

Around the box A is a collar or loosely- 65 mounted chambered member F, within which the box is free to turn with the rotation of the cylinder, to the head of which it is attached. The collar F is retained in position by a plate G, which is attached to the outer end of the 70 box A by screws. The length of the box A slightly exceeds the width of the collar F, which permits the free movement of the one within the other. The diameter of the collar F is somewhat in excess of the diameter of 75 the box A. The edges of the collar F are turned inward and then outward to form the bearing for the box A. This construction results in giving the collar an annular chamber H, into which open the circumferential perforations E.

An annular shoulder is formed upon the receptacle, box, or cup A by having a part of the periphery of said member A formed of less thickness than the part forming the 85 above-referred-to shoulder. This reduced portion of the said member is adapted to receive the collar F. It is apparent that the said shoulder and the detachable plate G prevent any lateral movement of the loosely-mounted chambered member F.

Attached to the collar is a tube I, which communicates with the annular chamber H and is provided at its lower end with a weight J, which may be held by a set-screw or in any 95 other convenient way. The tube I extends within about a quarter of an inch of the shell of the cylinder, its length being regulated according to the diameter of the latter, leaving a space for the passage of the water.

As will be readily seen, my device will at all times remain in one position during the rotary

- movement of the cylinder, the tube I and its weight J being sufficient to resist any friction that might be exerted upon the collar F by the rotary movement of the box A within it.
- 5 The gravitation of the water in the cylinder being toward the bottom, the pressure of the steam continually forces it up through the tube I into the annular chamber H, from which it is driven through the perforations E into the 10 box A and from thence to the hollow axis D of the cylinder, which then carries it off in a manner already well understood.
- This device is in no way dependent for its operation upon the rotation of the cylinder, but 15 it will operate equally well when the machine or the cylinder is at rest. It has no springs or other delicate parts to become damaged or disarranged and requiring repairs.
- What I claim as my invention, and desire 20 to secure by Letters Patent, is—
1. In a water-displacer for drying-cylinders, the combination of a flanged perforated box, an annular chambered member mounted upon said box and a weighted tube removably 25 secured to said annular member, substantially as described.
  2. A device of the character described comprising an apertured cylindrical receptacle, a chambered collar removably secured upon 30 said receptacle, a detachable conducting-tube secured to an extended portion of said collar, and means for positively retaining said tube in its normal position, substantially as described.
  3. A device of the character described comprising a flanged cylindrical receptacle apertured upon its periphery, a flanged chambered collar rotatably mounted upon said receptacle and a detachable conducting-tube 35 provided with an adjustable weight secured upon the periphery of said collar, substantially as described.
  4. A water-displacer for drying-cylinders comprising an apertured cylindrical receptacle, means for securing said receptacle to a cylinder, a plate secured to said receptacle retaining a loosely-mounted flanged chambered member thereon and detachable weight- 40 ed means for conveying water from the cylinder to said member and receptacle, substantially as described.
  5. A swivel water-displacer for drying-cylinders comprising a flanged receptacle having a series of apertures formed upon its periphery, a flanged chambered collar mounted upon said receptacle, means carried thereby for positively preventing lateral movement of said collar, and a weighted tube secured to said collar. 45
  6. A swivel water-displacer for drying-cylinders comprising a flanged receptacle having a series of apertures and a shoulder formed upon its periphery, a plate secured upon said receptacle retaining a loosely-mounted chambered member in engagement with said shoulder and plate, and means for communicating with the lowest part of a cylinder and said receptacle. 50
  7. In a device of the character described, the combination with a receptacle having a series of apertures formed upon its periphery, a rotatably-secured chambered collar mounted upon said receptacle, a circular plate detachably secured upon said receptacle and positively retaining the chambered collar 55 upon the receptacle, a removable pipe secured to an extension formed upon the collar, said pipe provided with an adjustable weight.
  8. A swivel water-displacer for drying-cylinders, comprising a cylindrical receptacle 60 said receptacle having a number of apertures formed upon its periphery, a shoulder upon said receptacle, a flanged annular recessed collar provided with an extended portion, a circular plate provided with means for detachably securing the same to said receptacle, a tube secured to the extended portion of the collar, means for locking said tube in position upon said collar and a removable weight secured upon said tube. 65

SAMUEL SMITH.
